UNITED STATES PATENT OFFICE.

FRANK H. BOGDA, OF HORICON, WISCONSIN.

STANCHION-ALINEMENT DEVICE.

1,359,224.

Specification of Letters Patent. Patented Nov. 16, 1920.

Original application filed June 1, 1918, Serial No. 237,690. Divided and this application filed July 11, 1919. Serial No. 310,066.

To all whom it may concern:

Be it known that I, FRANK H. BOGDA, a citizen of the United States, and resident of Horicon, in the county of Dodge and State of Wisconsin, have invented new and useful improvements in Stanchion-Alinement Devices, of which the following is a description, reference being had to the accompanying drawings, which are a part of this specification.

The present invention relates to certain new and useful improvements in stanchion alinement devices for adjusting the stanchion backwardly or forwardly with respect to the stall frame so that the animal may be properly positioned with respect to the gutter.

Heretofore in connection with devices of this kind to effect the adjustment, it has been necessary to loosen the bolts or screws on the alinement devices, or to take apart these devices to accomplish the adjustment and the object of this invention is to do away with this difficulty and provide an alinement device in which the parts may be moved to adjusted position and there secured without having to loosen up or take out and replace bolts or screws and without having to use any tools of whatsoever nature.

A further object of this invention is to provide an upper stanchion alining device which will provide means for connecting the adjacent meeting ends of a two-part stall frame.

With the above and other objects in view which will appear as the description proceeds, my invention resides in the novel construction, combination and arrangement of parts substantially as herein described and more particularly defined by the appended claims, it being understood that such changes in the precise embodiment of the hereindisclosed invention may be made as come within the scope of the claims.

In the accompanying drawing, I have illustrated one complete example of the physical embodiment of my invention, constructed according to the best mode I have so far devised for the practical application of the principles thereof, and in which:

Figure 1 is an elevation view of the upper portion of a stall and stanchion equipped with an alinement device embodying the invention.

Fig. 2 is an end view of the alinement device, parts being broken away and in sec-

tion to more clearly illustrate the details of construction.

Fig. 3 is a view similar to Fig. 2 illustrating the manner of unlocking the stanchion engaging member when it is desired to move the same to a new adjustment, and

Fig. 4 is a sectional view through the alining device taken on the line 4-4 of Fig. 2.

Referring now more particularly to the accompanying drawing, the numeral 8 designates the two like sections of a two-part stall frame adapted to have their inner adjacent ends connected together by means of my alining device designated as a whole as at 9; and 10, a stanchion suspended from the alining device, which is of any desired construction. The lower portion of the stanchion 10 may be also connected with the lower 75 alinement device illustrated in Patent No. 1,312,677, issued to me August 12, 1919, of which this application is a division.

The alinement device comprises a closed hollow casing 11 having projected from its sidewalls medially of its ends suitable stall frame engaging members 12 adapted to be clamped or secured thereto by means of binding bolts 13. This manner of securing the alining device to the stall frame provides means for connecting the two sections of the stall frame and also insures the proper positioning of the alinement device as will be at once apparent.

As best shown in Figs. 3 and 4, the casing 90 11 has formed in its bottom a longitudinally extending slot 14 provided with pairs of spaced apart opposed recesses 15 adapted to receive the rounded shank portion 16 of a bolt member 17 having its head disposed within the casing and its flattened shank 18 projected through the slot 14 and attached to the stanchion 10 as at 10'. The head of the bolt 17 is provided with a shoulder 19 adjacent the rounded portion 16 and with an extension or flattened upstanding lug 20 having the side flat faces thereof in a line with the side flat faces of the flattened shank 18 and adapted to be disposed beneath a depending rib 21 when in normal adjusted 100 position. The rib 21 is formed integral with the top wall of the casing and is disposed centrally above the slot 14 as best shown in Figs. 2, 3 and 4.

Formed in the bottom wall of the casing 110

11 adjacent each pair of opposed recesses 15, is a locking recess 15' formed by the raised portions 22 as best shown in Figs. 2, 3 and 4. The casing 11 is cast in one piece and has 5 formed in its sides in a line with the stall frame receiving portions 12 openings 23 whereby the bolt 17 may be passed therethrough in order that its head may be disposed within the casing and its shank projected outwardly thereof through the slot 14. For convenience in passing the bolt 10 through the openings 23, the portions of the shoulder 19 adjacent the flattened sides of the head 20 are flattened as best shown in 15 Fig. 4. The top portion 12' of the frame engaging members is preferably cast separate from the casing for convenience in securing the same to the frame members and for convenience in inserting the bolt 17 with 20 in the casing.

When the bolt 17 is in locked position suspending the stanchion 10 in its proper adjustment, the bolt 17 will be so disposed that the head 20 will be transversely disposed with respect to the rib 21. As best 25 shown in Figs. 2 and 4 the rounded shank portion 16 of the bolt member is disposed within the adjacent pair of recesses 15 and the shoulder 19 is seated within the adjacent locking recess 15' and the flattened shank or end 18 is disposed transversely with respect to the slot 14 when the bolt is 30 in any one of its adjusted positions. With the bolt in this position, it will be held 35 against movement longitudinally along the slot 14 as the shank 16 will be engaged within the recesses 15 and the shoulder 19 also engaged within the locking recess 15'. In order to unlock the bolt 17 from the adjusted 40 position, it is necessary that the same be raised a sufficient distance to disengage the shank 16 and shoulder 19 from their respective recesses and the accidental disengagement thereof is prevented by means of 45 the head 20 and the rib 21.

When it is desired to move the bolt 17 to a different adjustment, it must first be moved a partial revolution until the head 20 is in longitudinal alinement with the rib 21 and 50 the bolt is then tilted to one side and moved into the casing, as best shown in Fig. 3 until the shoulder 19 and rounded shank portion 16 disengage the recesses 15' and 15 respectively and then the bolt will be free to 55 move in either direction along the recess 14. When the bolt is adjacent the recesses 15 giving the proper adjustment to the stanchion, the same is drawn down and then turned to the position depicted in Fig. 2 60 when the same will be locked.

It will be readily apparent that it will be impossible for the animal to change the adjustment of the stanchion as it will be impossible to disengage the shoulders 19 and 65 rounded shank portion 16 from their re-

cesses without turning the bolt at least 90° and such an amount of movement is prevented as the animal is confined between the usual side stall members, not shown.

What I claim as my invention is:

1. A stanchion aliner comprising a supporting member, a tiltable stanchion carrying member for supporting the weight of a stanchion from the first mentioned member, said stanchion carrying member being movable to different positions of adjustment with respect to said supporting member, and a connection between said members for securing said stanchion in any one of several positions of adjustment, said stanchion being movable from one position of adjustment to another only upon said stanchion carrying member being first moved to a tilted position with respect to its normal position. 70

2. A stanchion aliner of the class described comprising a closed casing having a longitudinal slot in its bottom, a longitudinally extending rib in said casing above said slot, a stanchion engaging member having its upper end disposed within the casing, 80 means with which said member is engageable to define a plurality of adjusted positions, and means on said stanchion engaging member and adapted to engage said rib to be releasably locked in its adjusted position. 85

3. In a stanchion aliner, the combination with a two-part stall frame, of a longitudinally slotted casing disposed between the meeting ends of said frame and connecting the adjacent meeting ends of the frame, a 100 bolt member having its head disposed in said casing and its shank passed through said casing slot and adapted to receive a stanchion, spaced apart locking recesses disposed adjacent said slot and adapted to selectively receive the bolt head, and means within the casing and co-acting with the locking recesses to prevent the accidental unlocking of the bolt from adjusted position. 105

4. A stanchion aliner comprising a longitudinal slotted casing, a bolt member having its head disposed in said casing and its shank passed through said casing slot and adapted to be connected with a stanchion, 110 spaced apart locking recesses disposed adjacent said slot and adapted to selectively receive the bolt head, locking means within the casing and disposed above the locking recesses, and means formed on the head of said bolt member and co-acting with said locking means to prevent the accidental unlocking of the bolt member from adjusted position. 115

5. A stanchion aliner comprising a longitudinal slotted casing, a bolt member 125 having its head disposed in said casing and its shank passed through said casing slot and adapted to be connected with a stanchion, spaced apart locking recesses disposed adjacent said slot and adapted to selectively 130

receive the bolt head, locking means within the casing and disposed above the locking recesses, means formed on the head of said bolt member and co-acting with said locking means to prevent the accidental unlocking of the bolt member from adjusted position, said bolt member being movable a partial rotation to free the means on the bolt head from the locking means within the casing to permit the movement of the bolt from one locking recess to another.

6. A stanchion aliner comprising a longitudinally slotted casing, a bolt member having its head disposed in said casing and its shank passed through said casing slot and adapted to be connected with a stanchion, said bolt member head being selectively engaged in locking recesses adjacent said slot, and coöperating means between said bolt and casing to prevent an accidental unlocking of the bolt from adjusted position, said means including a locking rib within the casing and a projection on said bolt member head adapted to abut said locking rib.

7. A stanchion aliner comprising a longitudinally slotted casing, a bolt member having its head disposed in said casing and its shank passed through said casing slot and adapted to be connected with a stanchion, said bolt member head being selectively engaged in locking recesses adjacent said slot, and coöperating means between

said bolt and casing to prevent the accidental unlocking of the bolt from adjusted position, said means including a locking rib within the casing above the locking recesses and a projection on said locking bolt member adapted to be arranged transversely of said locking rib when the bolt is in normal position to prevent the bolt member from being shifted from one locking recess to another, said bolt member being movable a partial revolution and tilted and lifted into the casing a slight distance to permit the movement of same from one locking recess to another.

8. A stanchion aliner comprising a supporting member, a tilttable stanchion carrying member for supporting the weight of a stanchion from the first mentioned member, said stanchion carrying member being movable to different positions of adjustment with respect to said supporting member, and a connection between said members for securing said stanchion in any one of several positions of adjustment, said stanchion being movable from one position to another only upon said stanchion carrying member being first turned a partial rotation and then tilted with respect to its normal position.

In testimony whereof, I affix my signature.

FRANK H. BOGDA.
